ware

No Drawing. Filed Mar. 28, 1960, Ser. No. 17,787
7 Claims. (Cl. 260—370)

This invention relates to an improved process for preparing α -anthraquinone sulfonates, and derivatives thereof particularly 1,8-dihydroxy anthraquinone (Chrysazine), containing low amounts of mercury. In the sulfonation of anthraquinone, it is known as more fully described in U.S. Patent 2,742,484 of April 17, 1956, that when the sulfonation is effected in the presence of mercury or mercury compounds as described for example in U.S. Patent 742,910 of November 3, 1903, sulfonation in the α -position is favored, whereas if the sulfonation is effected in the absence of mercury, then sulfonation in the β -position is favored.

Accordingly, it is common to employ a mercury catalyst in the sulfonation of anthraquinone to produce 1-anthraquinone sulfonic acid and α, α' -anthraquinone disulfonic acids, e.g. the 1,5- or 1,8-anthraquinone disulfonic acid or their salts. However, the resulting α -sulfonic acid or salt or α, α' -disulfonic acid or salt still contains substantial amounts of mercury, which is usually about 1% or higher. This mercury is so combined in the α - or α, α' -anthraquinone sulfonic acid that it is extremely difficult to remove. Accordingly, there has been considerable demand in the art for an inexpensive process by which the amount of mercury contained in α - or α, α' -anthraquinone sulfonic acids or their salts, obtained by the sulfonation of anthraquinone in the presence of mercury, may be reduced to a minimum. The removal of the mercury has been particularly important in the case of 1,8-anthraquinone disulfonic acid, since this is employed as an intermediate for the preparation of 1,8-dihydroxy anthraquinone, also called Chrysazine, which is employed for medicinal uses. Thus, the National Formulary (1955) has imposed a strict specification requiring that 1,8-dihydroxy anthraquinone (Chrysazine) contain not more than 50 p.p.m. of mercury. In order to produce Chrysazine meeting these specifications from 1,8-anthraquinone disulfonic acid or its salt, it has been found necessary to employ 1,8-anthraquinone disulfonate containing less than 0.25% mercury.

We have now found that the mercury content of α -anthraquinone sulfonates, obtained by sulfonation of anthraquinone in the presence of mercury, and also derivatives of such α -anthraquinone sulfonates (e.g. 1,8-dihydroxy anthraquinone) can be substantially reduced by heating the mercury containing α -anthraquinone disulfonate (or derivative) in the presence of an oxidizing agent. We particularly prefer to use an alkali metal bichromate or permanganate, e.g. sodium or potassium bichromate or sodium or potassium permanganate as the oxidizing agent, however, other oxidizing agents such as nitric acid, hydrogen peroxide, sodium or potassium hypochlorite, chlorine, ammonium-, potassium- or sodium persulfate and the like may be used.

The details of the present invention will be apparent from the following specific examples of preferred embodiments thereof.

Example 1

50 g. of paste material of dipotassium 1,8-anthraquinone disulfonate (containing about 18 g. of 100% dipotassium 1,8-anthraquinone disulfonate having a mer-

2

cury content of about 1% and which had been recovered by treating with potassium chloride the acid liquor from 1,5-anthraquinone disulfonic acid manufacture after the 1,5-isomer had been separated in a manner similar to the procedure given in FIAT Report #1016, page 6), was slurried in 50 cc. of water and 10 cc. of a 5% solution of potassium permanganate in water was added. The mixture was heated to 95–100° C. for 1 hour, then cooled to room temperature and the dipotassium 1,8-anthraquinone disulfonate recovered by filtration, the filter cake being washed with water until free of permanganate. The cake was then dried in a vacuum oven at 85–90° C. and on analysis the dry cake was found to contain 0.093% mercury.

Example 2

The foregoing experiment was repeated using, however, in place of the potassium permanganate 10 cc. of a 5% solution of sodium bichromate in water. The analysis of the dried dipotassium 1,8-anthraquinone disulfonate which was recovered showed that it had a mercury content of 0.077%. The product of both Example 1 and Example 2 when employed for the production of Chrysazine gave a material meeting the specifications of the National Formulary, i.e. Chrysazine containing less than 50 p.p.m. mercury.

While as indicated in the above examples, the process of the present invention can be applied to dipotassium anthraquinone disulfonate in a concentrated form, it has been found as illustrated by the following example that the process of the present invention can be applied to the acid liquors containing the mercury containing 1,8-anthraquinone disulfonate having a high mercury content remaining after removal of 1,5-anthraquinone disulfonate from the products produced in the disulfonation of anthraquinone in the presence of mercury.

Example 3

925 cc. of the acid liquor from 1,5-anthraquinone disulfonic acid manufacture after the 1,5-isomer had been separated in a manner similar to the procedure given in FIAT Report #1016, page 6, and which consisted largely of mercury containing 1,8-anthraquinone disulfonic acid and a small amount of unsulfonated anthraquinone was diluted with water to a volume of 2925 cc. The thus diluted liquor was heated to 100° C. and 7.5 grams of sodium bichromate added thereto and the mixture stirred for $\frac{1}{2}$ hour at 100° C. The material was then filtered hot on a fritted glass filter and a small amount of undissolved, unsulfonated anthraquinone thus filtered out and discarded. The 1,8-anthraquinone disulfonic acid was then recovered in the form of its dipotassium salt by cooling the filtrate to 75° C. and adding at 75° C. in $\frac{1}{2}$ hour 45.5 g. of potassium chloride. The liquor was tested for complete precipitation of the insoluble potassium salt by adding a few crystals of potassium chloride to 5–10 cc. portions of the filter liquor. When the test showed complete precipitation in the batch, the batch was cooled to 55° C. and filtered on a fritted glass filter. The filter cake (dipotassium 1,8-anthraquinone disulfonate) was washed 8 times with 50 cc. portions of 1.5% potassium chloride solution in water at room temperature. The filter cake was sucked as dry as possible, then dried in a vacuum oven at 85–90° C. The dry filter cake on analysis had a mercury content of 0.23%. In a control run in which the treatment with sodium bichromate was omitted, the recovered dipotassium 1,8-anthraquinone disulfonate contained 1.01% mercury. The dipotassium 1,8-anthraquinone disulfonate containing 0.23% mercury was then used as base material for preparing Chrysazine in the customary manner by autoclaving with lime followed by dilution, acidification, boil-

ing off sulfur dioxide, filtering, washing with water, drying and subliming. The final sublimed Chrysazine contained 0.0047% mercury (47 p.p.m. mercury) and thus met the specifications of the National Formulary of below 50 p.p.m. mercury.

Example 4

To a stainless steel kettle equipped with agitator there was charged 3,330 parts by weight of water and 676 parts by weight of dry powder Chrysazine (1,8-dihydroxy anthraquinone) which was off standard since analysis showed that it contained 288 p.p.m. of mercury. There was also added 1½ parts by weight of the nonionic surface active agent obtained by condensing nonylphenol with about 10 moles of ethylene oxide to aid in wetting out the Chrysazine. The mixture was stirred until the Chrysazine was homogeneously dispersed in the water. There was then added 186 parts by weight of 26° Bé. nitric acid (35.5% HNO_3), or 65 parts by weight of 100% HNO_3 so as to give 1.85% nitric acid concentration in the kettle. The mixture was heated to 98° C. and held at this temperature while stirring for one hour. The charge in the kettle was then transferred to a filter and the kettle washed with about 100 parts by weight of hot water. After filtering, the filter cake was washed 3 times with 500 parts by weight of hot water until the filtrate was neutral to Congo red paper. The filter cake was sucked as dry as possible and the filter cake stored in lined drums. There was recovered 665 parts by weight (dry basis) of 1,8-dihydroxy anthraquinone or 98.5% of theory which analysis showed contained 40 p.p.m. of mercury.

While the present invention has thus far been described in connection with the removal of mercury from 1,8-dihydroxy anthraquinone and 1,8-anthraquinone disulfonic acids and its salts, since these materials are used for pharmaceutical purposes or as an intermediate for the preparation of a pharmaceutical, 1,8-dihydroxy anthraquinone, (Chrysazine), respectively, which must have a mercury content of less than 50 p.p.m., it will be understood that the process of the present invention can be applied to reduction of the mercury content of other α -sulfonated anthraquinones which have been produced by sulfonation of anthraquinone in the presence of a mercury catalyst. Thus by similar procedures the mercury content of 1-anthraquinone sulfonic acid or its salts, 1,5-anthraquinone disulfonic acid or its salts, or the mixed 1,5- and 1,8-anthraquinone disulfonic acids or salts can be reduced by treatment with an oxidizing agent in accordance with the present invention to reduce the mercury content of each of these isomers so that either the mixed isomers of low mercury content can be obtained or the individual isomers, each having a low mercury content, may be separated from this mixture.

55

We claim:

1. The method of reducing the mercury content of an anthraquinone compound selected from the group consisting of 1,8-dihydroxyanthraquinone and 1,8-anthraquinone disulfonic acid and its salts which have been produced by the sulfonation of anthraquinone in the presence of a mercury catalyst which comprises heating in an aqueous medium said anthraquinone compound together with a small amount of an inorganic oxidizing agent and separating said anthraquinone compound substantially free of mercury from said aqueous medium.
2. The method as defined in claim 1 wherein the oxidizing agent specified is potassium permanganate.
3. The method as defined in claim 1 wherein the oxidizing agent specified is sodium bichromate.
4. The method as defined in claim 1 wherein the oxidizing agent specified is nitric acid.
5. The method of reducing the mercury content of 1,8-anthraquinone disulfonic acid dipotassium salt produced by sulfonation of anthraquinone in the presence of a mercury catalyst which comprises heating an aqueous slurry of such mercury containing dipotassium 1,8-anthraquinone disulfonate with a small amount of an oxidizing agent selected from the group consisting of nitric acid, 20 potassium permanganate and sodium bichromate and separating said dipotassium 1,8-anthraquinone sulfonate substantially free of mercury from the aqueous phase.
6. The method of reducing the mercury content of dipotassium 1,8-anthraquinone disulfonate from the acid 25 liquors remaining after the removal of 1,5-anthraquinone disulfonic acid from the anthraquinone disulfonic acids produced by sulfonation of anthraquinone in the presence of a mercury catalyst which comprises heating said acid liquors with a small amount of an oxidizing agent selected from the group consisting of nitric acid, potassium permanganate and sodium bichromate, adding potassium chloride to the thus treated mixture to precipitate the dipotassium 1,8-anthraquinone disulfonate and separating the thus precipitated dipotassium salt substantially free 30 from mercury from the aqueous phase.
7. The method of reducing the mercury content of 1,8-dihydroxy anthraquinone produced from a 1,8-anthraquinone disulfonic acid which in turn was produced by sulfonation of anthraquinone in the presence of a mercury catalyst, which comprises heating an aqueous slurry of said 1,8-dihydroxy anthraquinone with a small amount of an oxidizing agent selected from the group consisting of nitric acid, potassium permanganate and sodium bichromate and separating said 1,8-dihydroxy anthraquinone substantially free of mercury from the aqueous phase.
